UNITED STATES PATENT OFFICE.

HENRY J. RITTER, OF TIPPECANOE CITY, OHIO.

KITCHEN-CABINET.

1,146,521.

Specification of Letters Patent. Patented July 13, 1915.

Application filed September 10, 1913. Serial No. 789,073.

To all whom it may concern:

Be it known that I, HENRY J. RITTER, a citizen of the United States, residing at Tippecanoe City, in the county of Miami and State of Ohio, have invented certain new and useful Improvements in Kitchen-Cabinets, of which the following is a specification, reference being had therein to the accompanying drawing.

10 This invention relates to kitchen cabinets and more particularly to the extensible work table forming a part of such cabinets and to the construction of the cabinet to receive the table.

15 The object of the invention is to provide a cabinet construction in which an open sanitary space or pocket will be provided to receive the rear portion of the extensible work table and to provide spacing devices 20 for forming this pocket which will further serve to detachably connect the upper and lower parts of the cabinet; and further, to provide means whereby the work table, when drawn to its outermost position, will be held against rattling.

25 In the accompanying drawings, Figure 1 is a sectional view of a cabinet embodying my invention and showing the work table in its retracted or normal position; Fig. 2 is a similar view showing the table in its extended position; Fig. 3 is an inverted perspective view of the table itself; and Fig. 4 is a detail view of the spacing and connecting device.

30 In these drawings I have shown the cabinet as comprising a lower part 1 and an upper part 2 mounted upon the lower part, preferably separable therefrom and provided with a vertical compartment 3 in 40 which is mounted a flour bin 4. The lower part of the cabinet is provided in its rear upper portion with a recess or pocket to receive the rear portion of an extensible work table 11 and this pocket is formed by mounting above the top of the main frame of the lower portion 1 a flat frame or supporting member 31 which is rigidly secured to the main frame of the lower portion of the cabinet by means of connecting devices or brackets 34, these brackets being screwed or otherwise secured to the edges of the main frame and the upper or supplemental frame. The frame 31 is spaced away from the main frame a distance somewhat greater 50 than the thickness of the table and the space between the main frame and the

frame 31 is open on all sides so that there is no opportunity for the accumulation of dirt or vermin. The upper portion 2 of the cabinet rests upon the supporting frame 31 and is preferably detachably secured thereto. To this end the connecting devices 34 are extended some distance above the frame member 31 and are provided with forwardly opening slots which are substantially horizontal and have their forward ends flared, as shown in Figs. 1 and 4. Inasmuch as the upper portion of the cabinet is of less width than the lower portion the connecting devices are bent inward and then upward, as shown clearly in Fig. 4. Each side of the upper portion of the cabinet is provided with lugs corresponding in number to the connecting devices and these lugs are so arranged that when the two portions of the cabinet are in their proper relative positions the lugs will lie within the horizontal slots of the fastening devices. Preferably, the lugs are in the form of screws which can be tightened down after the two portions of the cabinet have been placed in their proper relative positions to hold the same in such positions. This arrangement of the connecting devices or brackets is such as to form a sanitary pocket for the table and, moreover, to provide a connecting device which is not only separable to permit the cabinet to be knocked down and shipped in two parts but is of such a character that the two parts can be very quickly and easily assembled by one without mechanical knowledge. Thus, to assemble the cabinet it is only necessary to place the upper portion upon the frame 31 of the lower portion with the rear lugs 33 in the rear of the forward connecting devices 34, thereby bringing the lugs into alignment with their proper slots. By pushing the upper portion rearward the lugs are caused to enter the slots and will cooperate therewith to retain the two parts 100 in their assembled positions.

As is customary in kitchen cabinets the work-table 11 is slidably mounted so that it can be drawn outward to provide a wider working surface. Such tables are ordinarily provided with stops 44 near their outer edges to engage the front of the cabinet beneath the work-table and thus prevent the inward movement of the table when pressure is brought to bear upon the front edge thereof. In order that this stop may be operative, however, the table must have a

certain amount of pivotal movement to permit the stop to clear the top of the cabinet when the table is to be moved inward or outward. Consequently, this requires a loose support for the inner end of the table which vibrates and rattles noisily when the table is being used for many purposes, such, for instance, as the kneading of bread. To overcome this vibration and to firmly secure the table in its outer locked position I have provided the inner portion of the lower surface thereof near each side with an inclined projection 45 which increases in thickness toward its rear end. The walls of the cabinet 10 on each side thereof are provided with projections or pins 46 arranged to engage said inclined or tapered projections when said table is moved to its outermost position, thus forcing the rear end of the table upward 20 and causing it, when the stops 44 are in engagement with the front edge of the cabinet top, to engage the upper edge of its guide and thus hold the table firmly in position. If desired, a stop 47 may be provided to 25 limit the outward movement of the table. It will be noted that when in its outer position the rear edge of the table is supported by and pivots on the projection 46 and it is only when the front edge has been dropped 30 down to cause the stops 44 to engage the edge of the cabinet that the extreme rear edge of the table engages the top of the guideway. Consequently, the manipulation of the table to move it inward or outward is 35 as simple as formerly and it requires only that the front end of the table be lifted to enable it to be returned to its normal position. It will also be noted that this arrangement causes the table to slope forwardly and 40 as a result any water or liquids which are spilled upon the same will drain off the front edge of the table and will not run back into the interior of the cabinet.

It will be apparent from the foregoing description that I have provided a cabinet construction comprising two parts which may be readily separated and assembled and I have utilized the connecting devices for the two parts of the cabinet to provide a pocket 50 in which the rear portion of the work table may be placed when the table is not in use; further, that I have provided means co-operating with the walls of this pocket for securing the rear portion of the table against 55 vertical movement when the table is in its working position, thus preventing the rattling of the table when it is in use. Further, it will be apparent that the construction as a whole is exceedingly simple and of a 60 strong durable character.

While I have shown and described one embodiment of my invention it will be understood that this has been chosen for the purposes of illustration only, and that I do 65 not desire to be limited to the details of

construction shown and described, for obvious modifications will occur to a person skilled in the art.

The several features of the invention which are illustrated and not claimed, and particularly the device for connecting the upper and lower portions of the cabinet and the device for supporting the flour bin, form the subjects matter of separate applications for patent, filed Nov. 9, 1914, Ser. Nos. 75 871,007 and 871,008.

Having thus fully described my invention, what I claim as new and desire to secure by Letters Patent, is:—

1. In a kitchen cabinet, a main structure, 80 a table slidably mounted on said main structure for movement outward and then downward into engagement with the forward portion of said main structure, said main structure and said table having coöperating 85 parts controlled by the outward and downward movement of said table to cause the rear portion of said table to be held in engagement with a fixed part of said structure while the forward portion of said table is in engagement with the forward portion of 90 said main structure, and a stop to hold said table against rearward movement.

2. In a kitchen cabinet, a main structure having a guideway to the rear of the forward edge thereof, a table slidably mounted in said guideway, arranged when in its operative position to rest upon the forward portion of said main structure and having a stop to hold it against rearward movement 100 while it is in engagement with said forward portion of said main structure, said table having a forwardly tapered part near the rear end thereof, and a part carried by said main structure to engage said tapered part 10 of said table to cause the rear portion of said table to engage a fixed part of said main structure when said table is moved to place said stop in its operative position.

3. In a kitchen cabinet, a main structure 11 having a guideway to the rear of the forward edge thereof, a table slidably mounted in said guideway, arranged when in its operative position to rest on the forward portion of said main structure and having a 11 stop, the forward portion of said table being capable of vertical movement to enable said stop to be moved into and out of engagement with the forward edge of said main structure, a forwardly tapered projection secured 12 to the lower surface of the rear portion of said table, and a part carried by said main structure to engage said tapered projection and cause the rear edge of said table to engage a fixed part of said main structure 125 when said table is moved into engagement with the forward portion of said main structure, with said stop in engagement with the forward edge of said structure.

4. In a kitchen cabinet, a main structure 130

Having a guideway, a table slidably mounted in said guideway and having a stop adapted to engage the edge of said main structure to prevent the rearward movement of said table,
5 said table having forwardly tapered projections secured beneath its rear portion and near the opposite edges thereof, pins secured to the main structure and arranged to be engaged by the respective tapered projec-
10 tions to move the rear portion of said table into engagement with a fixed part of said cabinet.

5. In a kitchen cabinet, a main structure having a guideway, a table slidably mounted 15 in said guideway and having a stop adapted

to engage the edge of said main structure to prevent the rearward movement of said table, said table having forwardly tapered projections secured beneath its rear portion and near the opposite edges thereof, pins secured to the main structure and arranged to be engaged by the respective tapered projections, and stops to limit the outward movement of said table. 20

In testimony whereof, I affix my signature 25 in presence of two witnesses.

HENRY J. RITTER.
